UNITED STATES PATENT OFFICE.

CARL HENDERSON, OF CHICAGO, ILLINOIS, ASSIGNOR TO MIEHLE PRINTING PRESS & MANUFACTURING COMPANY, OF CHICAGO, ILLINOIS, A CORPORATION OF ILLINOIS.

SHEET-SEPARATING MECHANISM.

Application filed February 1, 1922. Serial No. 533,185.

To all whom it may concern:

Be it known that I, CARL HENDERSON, a citizen of the United States, residing at Chicago, in the county of Cook and State of Illinois, have invented certain new and useful Improvements in Sheet-Separating Mechanism, of which the following is a specification.

This invention relates to sheet separating mechanism which may be used in printing presses and the like.

As is well known, there is a tendency for raising not only one sheet but sometimes a second or a third sheet of paper from a pile when the top sheet is being withdrawn therefrom in the feeding of paper to a machine such for example as a printing press.

One object of this invention is to provide simple and efficient means which is positive in its action for separating a second sheet from the top sheet when the latter is being withdrawn from a pile of sheet material.

Another object of the invention is to provide a simple and reliable paper separating device adapted to meet the various requirements for commercial use.

These and other objects are accomplished by means of the arrangement disclosed on the accompanying sheet of drawing, in which—

Figure 1 is a front elevation of my sheet separating device;

Figure 2 is a vertical longitudinal sectional view taken in the plane of line 2—2 of Figure 1; and

Figure 3 is a transverse sectional view taken in the plane of line 3—3 of Figure 1.

The various novel features of my invention will be apparent from the following description and drawings and will be particularly pointed out in the appended claims.

In the sheet separating mechanism which I have here shown the second sheet of material is separated from the top sheet by a vibrating action.

Referring to the figures of the drawings it will be noted that the sheet separating mechanism includes a hollow tube 10 to the lower end of which is secured a rubber or flexible suction shoe 11, the attachment being made in any suitable manner, such as by a threaded collar 12 on which the shoe 11 is mounted and which is threaded onto the lower end of the tube 10. A shaft 13 is mounted concentrically within the tube 10 and

has both a vertical reciprocating movement and a rotary movement, the vertical movement being guided by a perforated spider 14 located within the tube 10. The rotary movement is guided by a member 15 which co-operates with the interior surface of the wall of the tube and is provided with openings 16 through which air may pass. The lower portion of guide member 15 is provided with a plurality of projections 17 giving the lower face of said member 15 in effect a cam shape. These projections 17 ride over a pin 18 which may be secured to the lower end of the tube in any suitable manner. As the projections 17 ride over the pin 18 the shaft 13 and the stem 19 at the lower end thereof are given a vertical vibratory action. The stem 19 and its shaft 13 are caused to rotate by air sucked up through the tube 10 which air acts upon a fan 20 secured to the shaft 13 below the guide spider 14. It is apparent therefore that as air is drawn upwardly through the tube 14 the fan 20 rotates the shaft 13, stem 19, and the member 15 secured thereto, causing, through the action of the projections 17 and pin 18, the stem 19 to have an up and down vibratory motion. It is this vibratory motion or action which causes the separation of a second sheet from a first sheet.

This vibratory action will continue so long as air passes upwardly through the tube 10, or in other words, so long as the sheet 21 does not seal the lower end of the suction shoe 11. If a second sheet is drawn upwardly with the first sheet 21 the vibratory pounding action of the stem 19 upon the top sheet 21 will cause the second sheet to be separated from the top sheet. A vibratory action of short duration will suffice to separate the second sheet from the first sheet, and accordingly the top sheet 21 may quickly seal the suction shoe 11, whereupon air will cease to pass upwardly through the tube 10 and the vibratory action of the stem 19 will cease. As soon as the top sheet 21 is withdrawn from the suction shoe 11 suction through the tube 10 will again be set up, causing a vibratory action of the stem 19.

It is my intention to cover all modifications of the invention falling within the spirit and scope of the following claims.

I claim:

1. In sheet separating mechanism, the combination of means for causing sheet ma-

terial to be withdrawn from a pile, and vibratory means for separating a second sheet from the first sheet if a second sheet adheres to the first sheet.

5. 2. In sheet separating mechanism, the combination of suction means for withdrawing sheet material from a pile, and vibratory means co-operating with said suction means for separating a second sheet from the first sheet if a second sheet adheres to the first sheet.

3. In sheet separating mechanism, the combination of a tube through which air passes for withdrawing sheet material from a pile, and vibratory means actuated by air passing through said tube for separating a second sheet from a first sheet if a second sheet has been withdrawn from the pile with the first sheet.

20. 4. In sheet separating mechanism, the combination of a tube through which air passes for drawing sheet material from a pile, a member mounted in said tube and driven by air passing therethrough, and means for vibrating said member for separating a second sheet of material from a first sheet if a second sheet is withdrawn from the pile with the first sheet.

5. In sheet separating mechanism, the combination of a tube through which air

passes for drawing sheet material from a pile, a member mounted in said tube and driven by air passing therethrough, means for vibrating said member for separating a second sheet of material from a first sheet if a second sheet is withdrawn from a pile with the first sheet, and means for guiding said member in its vibratory movements.

6. In sheet separating mechanism, the combination of a tube through which air may pass, a stem, means for actuating said stem, and a cam member associated with said stem whereby said stem is given a vibratory movement while air passes through said tube for separating a second sheet from a first sheet if a second sheet is withdrawn from the pile with the first sheet.

7. In sheet separating mechanism, the combination of a tube through which air passes for drawing sheet material from a pile, a suction foot mounted on said tube, a stem movably mounted in said tube, a fan in said tube by means of which said stem is rotated, and cam means whereby said stem is vibrated for separating a second sheet from a first sheet if a second sheet has been withdrawn from the pile with the first sheet.

Signed at Chicago, Illinois, this 28th day of December, 1921.

CARL HENDERSON.
